JAMES J. MULLEN AND FRANCIS M. STAMBAUGH, OF ST. LOUIS, MISSOURI, SAID
STAMBAUGH ASSIGNOR TO SAID MULLEN.

RIBBED OR CORRUGATED SHEET-METAL MEMBER.

Application filed January 7, 1927. Serial No. 159,587.

This invention relates to sheet metal members of the type that comprise straight corrugations or hollow ribs formed by bent or folded portions of the plate from which the member is constructed, one example of such sheet metal members being containers that are used as tanks or cases for transformers which are submerged in oil.

Such containers comprise a sheet metal side wall provided with longitudinally-disposed ribs or corrugations and various methods have been resorted to for closing the ends of the ribs. In one type of construction that has been used extensively, the corrugations extend throughout the entire length of the plate used to form the side wall and cast metal members are cast onto the end portions of said plate after it has been bent into the shape desired for the side wall, so as to close the ends of the corrugations and also form the top and bottom of the container, but the objections to such a container are that it is extremely heavy and bulky; it is expensive to manufacture, and the joints between the side wall and the cast end pieces are apt to leak. In another type of construction the corrugations on the side wall plate are flattened or mashed down at the end portions of the side wall and metal is added to the flattened portions of the corrugations, usually by a welding operation, so as to obtain plain rims or bands at the opposite ends of the side wall to which the end members, i. e., top and bottom of the container, can be attached, but such a construction is objectionable, in that it looks crude; it is expensive to manufacture and the end portions of the side wall comprise numerous thicknesses of metal. In another type of construction slits are formed in the corrugations in the end portions of the side wall and the slotted portions of said wall then folded or bent into overlapping relation, with a view to obtaining rims or bands at the ends of the side wall to which the end members can be attached, but such a construction is also of crude appearance and is very expensive to manufacture, on account of the relatively great amount of welding that is required to close the slits in the end portions of the side wall and build up sufficient metal on same to produce fairly smooth surfaced bands or rims to which the end members can be attached. In still another

type of construction the plate which constitutes the side wall of the container is notched out at its ends, the intermediate portions of the plate lying between said notches are then bent or folded so as to produce open-ended corrugations that terminate short of the ends of the side wall, and fillers are then fitted in the ends of the corrugations and secured to same by a welding operation, so as to form end closures for the corrugations. While such a construction produces a container that presents a mechanical-like appearance, the cost of fitting closures in both ends of each corrugation and then producing a welded joint around the entire edge of each of said closures makes this type of construction practically prohibitive for use as a tank or case for transformers.

One object of our invention is to provide a sheet metal container of the general type previously mentioned, i. e., one having a ribbed or corrugated side wall that is relatively inexpensive to manufacture; that presents a neat and mechanical-like appearance, and which is of such design that it is a simple matter to produce liquid-tight joints between the end portions of the side wall and the end members that constitute the top and bottom of the container.

We have herein illustrated our invention embodied in a container that is designed for use as a tank or case which is intended to be used as a housing for a transformer that is submerged in oil or other liquid, but we wish it to be understood that our broad idea is applicable to various types and kinds of sheet metal members used for other purposes.

When our invention is embodied in a transformer tank or case, as herein illustrated, the side wall of the tank is provided with a plurality of longitudinally-disposed corrugations or hollow ribs that terminate short of the ends of said side wall and which are closed at both ends by integral portions of the plate from which the side wall is formed, the end portions of the side wall beyond the ends of said corrugations constituting rigid, plain uncorrugated bands that are formed by end sections of the plate that merge into plain portions of the wall that lie between the corrugations. Any preferred type or kind of end members can be used to form the top and bottom of the tank, but we prefer to use flanged end plates that are con-

nected by rivets, welding or in any other suitable manner to the end portions of the side wall.

Figure 1 of the drawings is a side elevational view of a container embodying our invention that is adapted to be used as a transformer tank or case.

Figure 2 is an enlarged perspective view of a portion of the side wall plate after it has been bent to produce the corrugations on same; and

Figure 3 is a perspective view of a portion of said side wall plate after the joints in same have been seamed or closed.

Referring to the drawings, which illustrate the preferred form of our invention, A designates the side wall of a transformer tank or case which may be oblong, oval or of any other preferred cross-sectional shape and constructed from one or a plurality of metal plates, B designates the end members that constitute the top and bottom of said tank, and C designates longitudinally-disposed corrugations or hollow ribs on the side wall A. In such a container the corrugations C increase the area of the side wall that is presented to the air which circulates over the container, and thus, in effect, act as radiating fins which absorb heat from the oil or other liquid inside of the container that is used to cool the transformer which the container houses, but, as previously stated, it is immaterial what function is performed by the corrugations C. The corrugations C may vary in number, in dimensions and in arrangement, and in addition to increasing the radiating surface of the side wall of the tank, said corrugations also act to reinforce and stiffen the side wall.

As shown in the drawings, the corrugations C terminate short of the top and bottom edges of the side wall A, and the end portions of said side wall are plain or uncorrugated and constructed in the form of end bands or rims to which the end members B are attached, preferably by flanges 1 on said end members arranged either on the inside or on the outside of the end rims of the side wall and secured to same by riveting, welding or in any other suitable manner. The corrugations C are provided at their ends with closures formed by integral portions of the plate from which the side wall is constructed, and while said end closures can be formed in various ways without departing from the spirit of our invention, it is preferable to provide the side portions 2 of the corrugations with angularly-disposed, integral extensions 3 that merge into the end sections of the plate that constitute the end bands or rims to which the top and bottom of the tank are attached.

In the operation of constructing the side wall A of the tank, longitudinally-aligned notches are formed in the opposite ends of the plate which constitutes said side wall at

the points where corrugations are to be formed, prior to the operation of bending or folding said plate to produce the corrugation. The metal at the inner ends of said notches is also preferably bent and shaped by a combined bending and drawing operation, so as to produce the angularly-disposed portions 3 previously referred to, that constitute the end closures for the corrugations, it being preferable to form two angularly-disposed portions 3 at the inner end of each notch that increase gradually in depth or height from the center towards the side edges of the notch and which are drawn or stretched slightly at the points 3^a where they merge into the end sections 4 of the plate which lie between adjacent notches. Thereafter, when the intermediate portions of the plate lying in longitudinal alignment with said end notches is bent or folded to produce the corrugation C, the two laterally-bent portions 3 at the inner end of each notch come together into abutting relationship, and thus co-operate to form a closure for one end of the corrugation that is disposed at an angle and integrally connected to the rim or plain end portion of the side wall located beyond the end of the corrugation. In the operation of folding or bending the intermediate portion of the plate to produce a corrugation C, the adjacent end sections 4 of the plate lying at opposite sides of the notch in the end of the plate come together or move into substantially abutting relationship, as shown in Figure 2, and thus co-operate with each other to form part of the rim, band or uncorrugated end portion of the side wall, said end sections 4 lying in the same plane and merging into plain portions of the wall that lie at opposite sides of the corrugation, thereby forming very rigid end bands. Subsequently, the joint 5 between said end sections 4 and the joint between the angularly-disposed portions 3, are closed by a continuous seam 6, produced by a soldering, welding or brazing operation, said seams 6 also tending to stiffen the end rim of the side wall formed by the end sections 4 of the plate which are not subjected to a bending or deforming operation which tends to weaken the same. We make no claim herein to the method of constructing the container or to the apparatus used in the operation of bending or folding the intermediate portions of the plate that constitute the corrugations or ribs, as said method forms the subject-matter of our pending application for patent Serial No. 159,588, filed Jan. 7, 1927, and said apparatus forms the subject-matter of our pending application Serial No. 159,589, filed Jan. 7, 1927.

While we prefer to form the end closure of each corrugation C by two laterally-projecting extensions 3 on the side portions 2 of the corrugation that are joined together

by a seam 6 located at the longitudinal axis of the corrugation, we wish it to be understood that the end closures of the corrugations can be formed in various other ways without departing from the spirit of our invention. The essential thing is that the ends of the corrugations be closed by integral portions of the plate or plates of which the corrugations form a part, the particular shape of said integral portions being immaterial and the particular location of the seams or joints in the end closures and in the end portions of the plate being immaterial, so long as the side wall of the container is provided with integral, laterally-projecting corrugations provided with closed ends formed by integral portions of the plate, and arranged between plain or uncorrugated rims at the ends of said wall that are formed by end sections of the plate that lie in the same plane and merge into plain portions of the wall located between the corrugations. After the joints in the end closures of the corrugations and in the end rims of the side wall have been closed or seamed, said wall will be just as tight and will present practically the same appearance as a wall provided with corrugations or hollow ribs produced by a drawing operation. In other words, a sheet metal member or receptacle of the construction above described can be manufactured at a fraction of the cost of a member having end rims and provided with hollow ribs or corrugations that are produced by a drawing operation, because the end rims of my improved member or receptacle are formed by substantially straight or flat end sections of the plate, and the corrugations C and the parts of the plate that constitute closures for the ends of said corrugations are formed by a simple bending operation, followed by a seaming operation that is relatively inexpensive, on account of the short length of the joints in the end closures of the corrugations and between the end sections of the plate located beyond the ends of the corrugations. This, coupled with the fact that the side wall is absolutely liquid-tight throughout its entire area and is provided with rigid end bands comprising a single thickness of metal to which end members can be easily attached, makes such a receptacle particularly well adapted for use as a transformer tank or case. As previously stated, however, our invention is not restricted to a container or receptacle, but is applicable to any kind of a sheet metal member provided with a closed end corrugation or hollow rib.

Having thus described our invention, what we claim as new and desire to secure by Letters Patent is:

1. A sheet metal member having a side wall provided with laterally projecting ribs, or hollow corrugations, formed by folded or bent portions of the plate from which said receptacle is constructed, end closures for said corrugations formed by integral portions of said plate, and a rim located beyond one end of said corrugations and formed by abutting end sections of said plate that merge into the portions of the side wall located between said corrugations.

2. A sheet metal receptacle provided with end rims formed by abutting end sections of the plate from which said receptacle is constructed, laterally-projecting corrugations or hollow ribs on the side wall of said receptacle located between said rims and formed by bent or folded portions of the plate, and end closures for said corrugations formed by integral extensions on the side portions of the corrugations arranged in abutting relationship and joined together by seams which extend across said rims between the abutting end sections of the rims.

3. A sheet metal receptacle, comprising a side wall provided with laterally-projecting corrugations and flat portions between said corrugations, said corrugations being formed by bent or folded portions of the plate from which said side wall is constructed, end closures for said corrugations formed by integral bent portions of said plate that are joined together by seams, and a rim at one edge of said side wall formed by abutting end sections of said plate that are joined together by seams located in alignment with said corrugations.

4. A sheet metal receptacle having a side wall provided with laterally-projecting corrugations or hollow ribs formed by bent or folded portions of the plate from which said receptacle is constructed, closures for one end of said corrugations formed by integral extensions on the side portions of the corrugations, a rim at one edge of said side wall formed by end sections of the plate that merge into said extensions and which form continuations of the portions of the side wall located between the corrugations, and welded joints between the co-operating extensions at the ends of the corrugations and also between the adjacent end sections of the plate that form part of said rim.
